UNITED STATES PATENT OFFICE.

SAMUEL BOUTON, OF LYNN, MASSACHUSETTS, ASSIGNOR OF ONE-HALF TO
ALBERT B. BLACK, OF CONCORD, MASSACHUSETTS.

CIRCUIT MAKING AND BREAKING DEVICE.

No. 852,414.

Specification of Letters Patent.

Patented May 7, 1907.

Application filed February 10, 1906. Serial No. 300,377.

To all whom it may concern:

Be it known that I, SAMUEL BOUTON, a citizen of the United States, residing at Lynn, in the county of Essex and State of Massachusetts, have invented new and useful Improvements in Circuit Making and Breaking Devices, of which the following is a specification.

This invention relates to a device for making and breaking an electric circuit and causing a spark in the cylinder of a gas engine for the purpose of igniting the compressed gases therein, in a manner well known to those skilled in the art.

15 The object of the invention is to provide a simple and durable device for making and breaking the circuit, and one which may be readily adjusted to make and break the circuit at different times with relation to the 20 position of the piston in the cylinder of the engine, and thus increase or diminish the speed of the piston and the number of rotations of the crank shaft.

25 The invention consists in a rotary contact carrier, an operating contact stud fast thereto and rotating therewith, a stationary contact carrier, and a reciprocatory contact stud insulated from said operating contact stud and arranged to slide upon said stationary 30 contact carrier in a direction parallel to the axial center of said rotary contact carrier.

35 The invention again consists in the instrumentalities hereinbefore set forth, in combination with improved means for adjusting or regulating the position of said reciprocatory contact stud with relation to said rotary contact stud, both about the axial center of said revoluble contact stud and also laterally with relation thereto.

40 The invention finally consists in the combination and arrangement of parts set forth in the following specification and particularly pointed out in the claims thereof.

45 Referring to the drawings: Figure 1 is a side elevation of my improved circuit making and breaking device. Fig. 2 is a sectional elevation taken on line 2--2 of Fig. 1, looking toward the left in said figure. Fig. 3 is a diagrammatic view illustrating a gas engine 50 with my improved circuit making and breaking device attached thereto, the electric connections from the circuit making device to the electrodes being illustrated in diagram in said view.

Like numerals refer to like parts throughout the several views of the drawings.

In the drawings, 8 is a diagrammatic representation of a gas engine, in which 9 is the frame, 10 the cylinder, 11 the piston, 12 the connecting rod, 13 the crank, and 14 the 60 crank-shaft. A sparking plug 15 of well known construction is fast to the cylinder 10 and terminates in two electrodes 16 and 17. The electrode 17 is connected by a secondary wire 18 to an induction coil 19, said induction 65 coil being connected in turn, by connections 20 and 21, to a battery 22. A ground wire 23 connects the spark coil 19 with the frame 9 of the engine.

The circuit making and breaking device 70 consists, primarily, of a rotary contact piece and a stationary contact piece, said stationary contact piece being adjustable with relation to the rotary contact piece in order to produce the igniting spark at different times 75 with relation to the position of the piston in the cylinder, thus varying the speed of the engine according to the variation in time of the explosion of the gas caused by the spark, in the manner well known to those skilled in 80 this art.

The rotary contact carrier 24 consists, preferably, of a sprocket gear fast to a rotary shaft 25 journaled in brackets 26 fast to the frame 9. The contact carrier 24 and shaft 85 25 are rotated by a sprocket gear 27 fast to the crank shaft 14 and connected to the sprocket gear contact carrier 24 by a sprocket chain 28. A contact stud 29 is fastened to the contact carrier 24 and revolves with it. 90 In the left hand end of said contact stud 29 (Fig. 2) is provided a hemispherical recess 30 in which is located a ball 31.

The stationary contact carrier 32 is preferably formed of insulating material, in the 95 shape of a disk, and is fast to a bushing 33 loosely mounted upon the shaft 25, said bushing and stationary contact carrier being prevented from endwise movement upon said shaft at one side thereof by the contact carrier 100 24 and at the other side thereof by a washer 34 and nut 35. A reciprocatory contact stud 36 is arranged to slide upon said stationary contact carrier 32 longitudinally of the shaft 25, the same being arranged to slide in a 105 sleeve 37 fast to the carrier 32 by a screw 38 (Fig. 2). The right hand end of the reciprocatory contact stud 36 is provided with a

- conical flange 39 and the left hand end thereof is screw-threaded to receive an adjusting nut 40, which, it will be understood, regulates the distance to which the reciprocatory contact stud 36 may be moved toward the right (Fig. 2) by the spiral compression spring 41, one end of said spring bearing against the left hand side of the flange 39, the other end thereof bearing against the sleeve 37.
- 10 The end of the contact stud 36 opposite to that upon which the flange 39 is formed is provided with a contact point 42, arranged to contact upon the movement of said stud 36 toward the left, as hereinbefore described, 15 with a contact point 43 fast to a contact spring plate 44. The spring plate 44 is fastened to a binding post 45, said binding post being fastened to the contact carrier 32. A primary wire 46 connects the binding post 20 45 with the induction coil 19.
- The axial centers of the contact studs 29 and 36 are equidistant from the axial center of the shaft 25. It will be evident that as the contact carrier 24 is rotated, as hereinbefore described, together with the shaft 25, the ball 31 will come in contact with the conical flange 39 and that as said ball and contact stud 29 pass the contact stud 36 the same will yield, by reason of the compression of the 25 spring 41, and will remain constantly in contact with said ball until the same is passed by in its rotation. The length of contact of the ball 31 with the flange 39 may be regulated by means of the adjusting nut 40, and any 30 wear upon the ball 31 or upon the flange 39 may be compensated for by said adjusting nut. It will again be observed that the contact stud 29 and ball 31 are operative in contacting with the flange 39 in either of the two 35 directions of rotation taken by the shaft 25 and contact carrier 24.
- In order to vary the time of the igniting spark with relation to the piston 11 the contact carrier 32 is adjusted about the axis of the shaft 25 by means of a lever 47, pivoted at 48 to the frame of the machine, said lever 47 being connected by a rod 49 to an arm 50 fast to the stationary contact carrier 32. The lever 47 is locked in position by a spring 50 slide bolt 51 and notched segment 52.
- The operation of my improved circuit making and breaking device, hereinbefore specifically described, is as follows: The contact carrier 24 is rotated by means of the 55 sprocket gear 27, (fast to the crank-shaft 14) and sprocket chain 28. As said contact carrier 24 is rotated, the stud 29 is revolved therewith, together with the ball 31. The ball 31 comes into contact, during its rotation, with the conical flange 39, pushing said flange, together with the stud 36 and contact point 42, toward the left (Fig. 2) until said contact point 42 contacts with the contact point 43, completing the circuit through the 60 spring plate 44, binding post 45, primary wire

46, through the induction coil 19, connection 21, battery 22, connection 20, through the induction coil again and through the ground wire 23 to the frame 9; from the frame 9, through the shaft 25 and sprocket gear or contact carrier 24 to the stud 29. The secondary circuit passes from the induction coil 19, through the connection 18 to the sparking plug 15, passing from the electrode 17 to the electrode 16, said electrode 16 being fast to the outer casing of the sparking plug. The circuit is completed through the frame 9 and ground wire 23 to the induction coil 19. It will be seen and understood that the contact stud 29 during a portion of the rotation of said contact carrier 24 makes mechanical and electrical contact with the reciprocatory contact stud 36.

Having thus described my invention what I claim and desire by Letters Patent to set 85

1. In a circuit making and breaking device a rotary contact carrier, an operating contact stud fast thereto and rotating therewith provided with a hemispherical recess, a ball 90 located in said hemispherical recess, a stationary contact carrier, and a reciprocatory contact stud, insulated from said operating contact stud and arranged to slide upon said stationary contact carrier in a direction parallel 95 to the axial center of said rotary contact carrier, said ball constructed to make, during a portion of the rotation of said rotary contact carrier, mechanical and electrical contact with said reciprocatory contact stud. 100

2. In a circuit making and breaking device, a rotary contact carrier, an operating contact stud fast thereto and operating therewith, a stationary contact carrier, a reciprocatory contact stud insulated from said 105 operating contact stud and arranged to slide upon said stationary contact carrier in a direction parallel to the axial center of said rotary contact carrier, and means to adjust said reciprocatory contact stud about the axis of 110 said rotary contact carrier, said operating stud constructed to make, during a portion of the rotation of said rotary contact carrier, mechanical and electrical contact with said reciprocatory contact stud. 115

3. In a circuit making and breaking device, a rotary contact carrier, an operating contact stud fast thereto and operating therewith, a stationary contact carrier, a reciprocatory contact stud insulated from said 120 operating contact stud and arranged to slide upon said stationary contact carrier in a direction parallel to the axial center of said rotary contact carrier, and means to adjust said stationary contact carrier about the axis of 125 said rotary contact carrier, said operating stud constructed to make, during a portion of the rotation of said rotary contact carrier, mechanical and electrical contact with said reciprocatory contact stud. 130

4. In a circuit making and breaking device, a rotary contact carrier, an operating contact stud fast thereto and operating therewith, a stationary contact carrier formed of insulating material, a reciprocatory contact stud arranged to slide upon said stationary contact carrier in a direction parallel to the axial center of said rotary contact carrier, a spring acting to move said reciprocatory contact stud longitudinally of said axial center, a contact spring fast to said stationary contact carrier, and a binding post fast to said contact spring, said reciprocatory contact stud arranged to make mechanical and electrical contact at one end thereof with said operating contact stud during a portion of the rotation of said operating contact stud and at its opposite end with said contact spring.
5. In a circuit making and breaking device, a rotary shaft, a contact carrier fast thereto, an operating contact stud fast to said contact carrier and operating therewith, a stationary contact carrier formed of insulating material mounted upon said shaft, and a reciprocatory contact stud arranged to slide upon said stationary contact carrier, longitudinally of said shaft, and to make mechanical and electrical contact with said operating contact stud during a portion of the rotation of said contact carrier.
6. In a circuit making and breaking device, a rotary shaft, a contact carrier fast thereto, an operating contact stud fast to said contact carrier and operating therewith, a stationary contact carrier formed of insulating material mounted upon said shaft, a reciprocatory contact stud arranged to slide upon said stationary contact carrier, longitudinally of said shaft, and means to adjust said stationary contact carrier about the axis of said shaft, said operating contact stud constructed to make, during a portion of the rotation of said rotary contact carrier, mechanical and electrical contact with said reciprocatory contact stud.
7. In a circuit making and breaking device, a rotary shaft, a contact carrier fast thereto, an operating stud fast to said contact carrier and operating therewith, a stationary contact carrier formed of insulating material mounted upon said shaft, a reciprocatory contact stud arranged to slide upon said stationary contact carrier, longitudinally of said shaft, a spring acting to move said reciprocatory contact stud longitudinally of said shaft, a contact spring fast to said contact carrier, and a binding post fast to said contact spring.
8. In a circuit making and breaking device, an axle, a contact carrier pivotally mounted upon said axle, means to adjust said contact carrier about said axle, and a contact stud insulated from and arranged to slide upon said carrier longitudinally of said axle.
9. In a circuit making and breaking device, an axle, a contact carrier pivotally mounted upon said axle, means to adjust said contact carrier about said axle, a contact stud insulated from and arranged to slide upon said carrier longitudinally of said axle, and a spring acting to move said contact stud longitudinally of said axle.
10. In a circuit making and breaking device, an axle, a contact carrier formed of insulating material pivotally mounted upon said axle, means to adjust said contact carrier about said axle, a contact stud arranged to slide upon said carrier longitudinally of said axle, a spring acting to move said contact stud longitudinally of said axle, a contact spring fast to said contact carrier arranged to contact with one end of said contact stud, and a binding post fast to said contact spring.
11. A circuit making and breaking device comprising in its construction a contact carrier, a pivot therefor, means to adjust said contact carrier about said pivot, and a contact stud insulated from and arranged to slide upon said carrier longitudinally of said pivot.
- In testimony whereof I have hereunto set my hand in presence of two subscribing witnesses.

SAMUEL BOUTON.
